US0D1086085S

(12) **United States Design Patent** (10) **Patent No.:** **US D1,086,085 S**
(45) **Date of Patent:** **** Jul. 29, 2025**

(54) **ACTIVE COOLER**

(71) Applicant: **Tong Zhu**, Guangdong (CN)

(72) Inventor: **Tong Zhu**, Guangdong (CN)

(**) Term: **15 Years**

(21) Appl. No.: **29/907,884**

(22) Filed: **Jan. 9, 2024**

(51) LOC (15) Cl. **13-03**

(52) U.S. Cl.

USPC **D13/179**; D23/370

(57) **CLAIM**

The ornamental design for a active cooler, as shown and described.

DESCRIPTION

FIG. 1 is a first perspective view of a active cooler showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the active cooler that form no part of the claimed design.

1 Claim, 8 Drawing Sheets
